ATTORNEY.

UNITED STATES PATENT OFFICE

2,126,871

ELECTRIC SIGNAL SWITCH

Tommy J. Converse, Bellingham, Wash.

Application June 21, 1937, Serial No. 149,305

1 Claim. (Cl. 200—153)

My invention relates to improvements in electric signal switches for use with donkey logging engines—especially those operated by gasoline—and has for an object to provide a switch which 5 may be disposed on the engine and operated by a pull on a signal wire to close an electric circuit through a locally-disposed battery and electric horn.

Another object of my invention is to provide 10 for the proper operation of the switch by a pull on the signal wire when the same is extended in any desired direction from the engine.

Other objects of my invention will appear as 15 the description proceeds.

I attain these and other objects of my invention with the mechanism illustrated in the accompanying sheet of drawings, which forms a 20 part of this specification, in which Figure 1 is a side elevation of my electric switch, Fig. 2 is a plan view of Fig. 1, Fig. 3 is a fragmentary portion of Fig. 1 shown partly in section on a medial, horizontal longitudinal plane, drawn on a larger 25 scale, and Fig. 4 is a diagram of the electric wiring connections.

Similar characters refer to similar parts 30 throughout the several views. Certain parts are broken away to show other parts hidden thereby.

With more particular reference to designated 35 parts: The inclined flat spring 5 has a curved upper end 6 overlade with a suitable electric-contact metal 7 and mounted on the cap 8 which has downwardly bent ends 9 to drain off any water which may come thereon. The upper end of the spring 5 extends above the cap 8. The 40 spring 5 and the cap 8 are fastened on top of the crossarm 10, with insulation plate 14 intervening, by the bolts 15 and 16 which are extended through holes therein. The end of the bolt 15 is extended beyond its clamping nut and is provided with a 45 nut for use as a binding post. The bolts 15 and 16 are insulated from the crossarm 10 by the bushings 17, 17 and the insulation discs 18, 18.

The crossarm 10 is on the frame arm 11 which 50 is extended from the annular bearing 12. The binding post 13 is conveniently disposed on the arm 11 and electrically connects with the frame 55 of the switch. Another annular bearing 20 is disposed beneath the said bearing 12 in alignment therewith and both are fastened to the frame post 19 which is extended above the bearing 12 and has the bearing ears 24, 24 on the upper end thereof. The upper end of the oscillatory arm 25 is disposed between the bearing ears 24 and pivoted for oscillation thereon by the pin 26. The lower end 25^a of the arm 25

is of increased width and has the long slot 27 therein. The stud 28 is fastened to the post 19 and extends through the slot 27 with its outer end threaded and engaging the set-nuts 29 to limit the outer oscillations of the arm 25. The finger 30, on the upper end of the arm 25, extends over the curved end 6 of the spring 5 and has the enlarged end 31 to bear on and contact with the contact metal 7 of the spring 5 and make electrical connection therewith when the 10 arm 25 oscillates outwardly. The bearing ears 32 extend outwardly from the lower end of the post 19. The inner end of the spring rod 33 is extended through the said slot 27 and has the eye 34 thereon which is disposed between the 15 said ears 32 and pivoted thereto by the pin 35. The spring rod 33 has its outer end threaded and extended through a hole in the upper end of the bearing plate 36 and boss 37 thereon and is retained in place by the set-nuts 38 engaged 20 on its said threaded end. The helical spring 39 with the bearing washers 40 and 41 disposed on its ends is mounted on the spring rod 33 between the slotted end 25^a of the arm 25 and the boss 37 of the bearing plate 36. The desired 25 pressure on the spring 39 is attained by adjusting the set-nuts 38. The tension rod 42 has the eye 43 on its inner end which is disposed in the lower end of the slot 27 and pivoted to the lower end 25^a of the arm 25 by the pin 44. The outer 30 end of the rod 42 has a hole therein and is extended through a guide hole in the lower end of the plate 36 to dispose it alongside of the spring rod 33 and spaced therefrom. An end of the signal wire 45 is fastened to the outer end 35 of the tension rod 42 engaged in the said hole in the end thereof. A stud shaft 21 has the annular boss 22 thereon and a threaded lower end 21^a which, preferably, is engaged with a fixed part of the said donkey engine. The upper end 40 of the shaft 21 is extended through the aligned bearings 20 and 12 disposing the bearing 20 to bear on the boss 22. The spring cotter pin 23 is extended through a hole through the shaft 45 above and proximate to the bearing 20 to retain the mechanism in place on the shaft.

In diagrammatic Fig. 4, the battery 46 has a terminal connected with one binding post 49 of the electric horn 47, the other binding post 48 of the horn is connected with the frame binding 50 post 13, which thus is electrically connected with the finger 30 and the contact end 31 thereof, and the contact 7 of the spring 5 is connected through the binding post 15 with the other battery terminal. Preferably the horn 47 is mounted on 55

the engine and the battery is disposed adjacent thereto.

- In operation: Assuming the shaft 21 to be set vertically on an upper part of the donkey engine 5 with the boss 22 disposed to provide a clear space for the mechanism to swing around the shaft 21. Then the signal wire 45 may lead in any desired direction from the engine and a pull thereon will tend to compress the spring 39 and move the arm 10 25 outward toward the set-nuts 29, say, to the position indicated in dotted lines at 25'; then the pin 44 will be at 44', the rod 42 at 42', the wire 45 at 45', the finger 30 at 30', bearing on the curved part 6 of the spring 5 and moving it to its dotted-line position at 6', and making electrical connection between the finger 30 and the spring 5 thus closing the electric circuit and sounding the electric horn 47. When the pull on the wire 45 ceases the reaction of the spring 39 15 20 will tend to return the arm 25 and all other movable parts of the mechanism to their solid-line positions and the connection between the finger 30 and the spring 5 will cease and the horn will stop sounding.
- 25 As stated, the entire switch is free to revolve on the shaft 21 as indicated by the arrows in Fig. 2, and the part of the structure supported by the rods 33 and 42 is quite free to swing on the pins

35 and 44 as indicated by the arrows in Fig. 1. The position of the latter part, as shown in Fig. 1, is quite nearly that which it assumes when held operatively tense by a tightly stretched signal wire. 5

Having thus disclosed my invention, what I claim as new therein and desire to secure by Letters Patent is,—

An electric signal switch including, a switch frame, an electric contact spring fastened to the 10 said frame insulated therefrom, an arm pivoted on the said frame for oscillation, a finger extension on one end of the said arm disposed to make electric contact with the said contact spring by the oscillation of the said arm, resilient means 15 operable between the said frame and the said arm tending to retain the said finger out of contact with the said contact spring, a signal wire attached to the other end of the said arm to oscillate the said arm against the said resilient 20 means and force the said finger to contact the said contact spring, a stud shaft adapted for fastening on a supporting structure, and aligned bearings on the said frame having their axis disposed in the plane of oscillation of the said arm 25 mounted for revolution on the said stud shaft.

TOMMY J. CONVERSE.
